The ornamental design for a freestanding faucet, as shown and described.

DESCRIPTION

FIG. 1 is a perspective view of a freestanding faucet showing our new design;

FIG. 2 is a front elevational view thereof;

FIG. 3 is a rear elevational view thereof;

FIG. 4 is a side elevational view thereof;

FIG. 5 is another side elevational view thereof;

FIG. 6 is a top plan view thereof;

FIG. 7 is a bottom plan view thereof; and,

FIG. 8 is an enlarged perspective view taken from FIG. 1. The evenly spaced broken lines in the drawings are for the purpose of illustrating portions of the freestanding faucet that form no part of the claimed design. The dash-dot broken lines showing the enlargements in FIGS. 1 and 8 form no part of the claimed design.
